UNITED STATES PATENT OFFICE.

GEORGE HOLT FRASER, OF NEW YORK, N. Y.

SCREENING APPARATUS.

1,202,377.

Specification of Letters Patent.

Patented Oct. 24, 1916.

Original application filed September 24, 1908, Serial No. 454,604. Divided and this application filed June 10, 1915. Serial No. 33,294.

To all whom it may concern:

Be it known that I, GEORGE HOLT FRASER, a citizen of the United States, residing in the borough of Brooklyn, county of Kings, 5 city and State of New York, have invented certain new and useful Improvements in Screening Apparatus, of which the following is a specification.

This application is a division of my application Serial No. 454,604, filed September 24, 1908.

This invention relates to screens for separating coarse from fine materials, and aims to provide certain improvements therein.

15 The invention is especially applicable to inclined screens of the class in which the material to be screened is distributed across the upper end of the screen by a screw conveyer and flows down the screen while the latter is vibrated to prevent clogging. Such inclined screens are usually adjustable to vary the steepness of the screen, and are usually supported by springs and vibrated by eccentrics or hammers.

20 25 This invention aims to provide screens of this type which shall be more nearly universal in adaptation to the particular requirements of use, more easily accessible for adjustment and renewal, and more effective in operation, than heretofore.

To this end the invention provides various improvements which shall be herein-after more fully set forth with reference to the accompanying drawings, in which,—

30 35 Figure 1 is a side elevation of the preferred form of my invention; Fig. 2 is a rear elevation thereof partly broken away to show the machine in section on substantially the planes of the line 2—2 in Fig. 1. Fig. 3 is a vertical section thereof cut on the line 3—3 in Fig. 2 and looking in the direction of the arrow; Fig. 4 is a fragmentary perspective view of the feed hopper and trough; Fig. 5 is a cross-section cut on the line 5—5

40 45 in Fig. 1 and looking in the direction of the arrow; Fig. 6 is a cross-section cut on the line 6—6 of Fig. 3 and looking in the direction of the arrow; Fig. 7 is a fragmentary face view of one of the screen frames partly broken away and on a larger scale; Fig. 8 is a fragmentary section thereof, and

Fig. 9 is a fragmentary sectional view of the knocking device, and Fig. 10 is a perspective view of the feed trough, and Fig. 11 a similar view of a modification of the trough.

Referring to the drawings, A is the feed hopper, B the conveyer for distributing the feed, C the drive pulley, D the drive shaft, E the feed trough, F the rear feed plate, G 60 the front feed plate, H the screen carrier, I the screens, J the vibrators, K the springs, L the fine outlet, M the coarse outlet, N the side walls, O the bottom wall, P the top door, Q the lower door, R the back door, S 65 the front and rear doors, T the feet, and U the legs.

The material to be screened enters the hopper and is pushed along the trough by the revolving conveyer, which throws it over 70 the edge of the trough as it travels, so that it falls onto the feed plate in a substantially uniform quantity at all points throughout the width of the screen. The material slides down the feed plate and onto the screen 75 cloth, down which it flows, the fine material falling through the meshes of the screen and the coarse material sliding down the upper face of the screen. The fine material flows down the bottom to the outlet L, and the 80 coarse material flows off the screen and passes through the outlet M. The screen is vibrated to prevent clogging, and is adjusted up or down on the legs U to the desired steepness.

85 As shown, the hopper A is a casting having flanges *a* depending at front and at rear of the conveyer, side flanges *b* above the conveyer, and top flanges *c* surrounding its inlet for receiving the end of a chute, and is 90 adapted to be placed at either end or at the middle of the separator and to receive feed from any direction.

95 As shown the feed trough is provided with discharge edges *d* at both its front and rear sides, which edges are inclined from the feed point downwardly toward the end and are adjustable in inclination so that the angle of the edge may be suited to cause a uniform discharge of material throughout the 100 length of the trough. Preferably the trough is made with reverse inclined edges, so that

when the hopper is at one end and the conveyer revolved in one direction, the material can be discharged over the rear edge of the trough, and when the hopper is at the other end and the revolution of the conveyer is reversed, the material can be discharged over the front edge of the trough. I prefer to construct the trough of a single sheet curved to suit the conveyer, and sufficiently flexible to permit its ends to be relatively distorted for adjusting the angularity of its edges, and to effect this adjustment by retaining screws *e* which hold it in place. At each end at the low side the trough is cut out to form an outlet *f* for any material that has not been thrown over the edge, and this outlet at the hopper end is closed by a shield *g* pivoted to the hopper at *h* and engaged by the adjacent screw *e*, which shield prevents material falling through the hopper from escaping at this side of the trough. With this construction it is possible to place the hopper at either end of the trough and run the conveyer in either direction, so that it will feed the material over the edge which inclines downwardly from the hopper, thus making it immaterial whether the drive is right or left hand.

As shown two feed plates are provided beneath the conveyer, the rear plate *F* receiving the material from the trough *E* when it is discharged over the rear edge of the trough and directing it forwardly down onto the screen, and the front plate *G* receiving the material when it is discharged over the front edge of the trough and directing it backwardly onto the plate *F*, from which it slides onto the screen, so that the material is delivered to the screen in the same manner whether the discharge is over the front or the rear edge of the feed trough. The plates *F* and *G* incline toward each other in order to bring the material always to the same place for delivery to the screen. When the material is discharged over the front edge of the trough, to prevent the fall of the material directly onto the screen, the hinged edge *h''* of the plate *F* will be used on the rear plate, but when the material is to be fed over the rear edge of the trough the plates will be reversed, or the hinged edge of the plate *F* will be unhooked and fastened on the plate *G*, where it will hang thus enabling the material to flow onto the screen nearer the uppermost end thereof. This hinged edge rests on the screen frame and is vibrated thereby.

According to one feature of improvement, the screen frame *H* consists of an open frame having grooved slideways *i* in which the various sections of the screen *I* slide and by which they are guided. The adjacent edges of screen sections are engaged by clamping strips *j* held down by screws *k* passing be-

tween the sections and screwing into the slideways. At the sides I provide clamping angles *l* which fit against the side angles *m* of the spring frame and carry the fingers *n* by which the frame is depressed. The guides *i* and side angles *m* are united by a top angle *o* and a bottom angle *p*, and the frame is adjustably maintained in position by hanging rods *q* hooking into screw eyes *r* so that the frame is free to move up and down. The spring frame is preferably held up against a stop wall *s* by the springs *K* through the medium of spring rods consisting of adjustable eyes *t* passing through the sides *m*, and adjustable hooks *u* passing through the front and carrying the springs *K*. Thus the frame is elastically supported so that it can be depressed, and when released will be drawn up suddenly against the stop wall by the springs, and will thus be given an abrupt upward jolt to free the screen from any clogged material. Unhooking the spring rods and the supporting rods *q* frees the spring frame for removal. When thus freed it will drop down until supported by its lower bar *p*, when it can be swung down like a door and removed either through the front or rear.

Several features of improvement are embodied in the agitating devices *J*, which consist of oscillating knockers *v* mounted on rocker shafts *w* and preferably having walls embracing the fingers *n*, and serrated striking faces which engage these fingers for repressing the screen. The faces *x* and fingers *n* are preferably relatively disposed to permit variation of the depressing movement by adjusting the fingers toward or from the shaft by bending them or otherwise, so that when the fingers are in one position the maximum movement will occur, and when in another position the minimum movement will occur, as indicated in dotted lines in Fig. 9. This device aims to depress the frame with a diminishing speed and to release it with an increasing speed, so that the screen will receive a sharp upward blow against the wall *s* when released. This is accomplished by oscillating the knocker *v* by the arm *y* which is oscillated from a crank *z* on the drive shaft *D*, the parts being preferably so disposed that the knocker engages the finger as the crank approaches the dead center, and releases the finger as the crank is moving toward the full throw position, the lost motion between the knocker and finger being arranged so that the knocker will be ineffective during its rapid movements, and effective during its slow movements, thus avoiding too great a vibration of the spring frame and preventing too much strain on the knocker. The knocker arms *y* are connected by a connecting rod *a'*, and are connected with the crank by a pitman *b'*. Each arm

preferably has an integral oil cup c' closed by a cover d' , and the pitman has a similar oil cup at its crank end.

Another feature of improvement consists in constructing each end of the casing preferably of a single casting having an inclined top flange e' , a wall f' extending therefrom to the wall s , an outwardly offset wall g' below the wall s , and a lower edge or flange h' of greater angularity than the wall S , and at its upper end with an inwardly projected portion i' having front and rear flanges j' for supporting the plates F and G , and a deflecting flange k' at the intersection of these flanges for overlapping the plates at this point and deflecting material inwardly toward the screen. The trough bracket l' is formed or cast on the inner face i' to support the feed trough, and has ears for receiving the adjusting screws e . Externally the side N has cylindrical brackets m' spaced apart from the wall to leave an air space for the escape of dust, in which brackets fit bearings n' having portions shaped like a segment of a sphere, so that they may oscillate in any direction to aline themselves with the shafts they carry. These bearings have integral oil cups o' provided with lugs for attaching them to the wall.

The casing is preferably composed of two ends N united by a rigid bar p' at the bottom and a rigid T-bar q' at the top, which bars space the ends and determine their positions. The bar p' makes the division between the fine outlet L and the coarse outlet M , and acts as a stop by engaging the lower bar p of the spring frame to prevent the frame from falling downwardly when released, and to support its lower end when the frame is being swung up and down. The bar q' supports the feed plate F and carries the adjacent top door S , the lower edge of which door is hinged to this bar and bent inwardly over the plate to prevent leakage above the latter. The back door R slides up under the bar r' and has an inwardly bent end which rests on the inner face of the bar q' . The front plate G is supported by an angle bar s' which is bolted to the top edge of the slides N and carries the upper springs K . The lower springs K are carried by a T-bar t' which is bolted to the upper edges of the ends near their bottom. The top covers P rest on the bars $s' t'$, and intervening cross bars u' and v' , there being preferably four of these covers. The lower cover Q rests on the bar t' and on a front bar w' . The bottom O preferably is hinged at x' in a cavity formed in the inner face of the side, and is fastened against the edges of the sides and against the under side of the bar q' , so that this bottom can be swung down to give access beneath the screen.

The entire casing preferably is pivotally

mounted on a bolt y' as a fulcrum, which connects it to the feet T so that it can be swung up or down to vary the steepness of the screen. At its upper end it is adjustably connected by the bolt z' to the leg U , which has a row of holes, in any one of which this bolt may be passed to hold the casing at the desired angle.

Another improvement consists in constructing the screen frame with extending rods or compression members a'' fastened in sockets in the side bars b'' , and of such length that the frame can not be distorted inwardly to less than its minimum width, but adapted to positively spread the frame until the screen cloth is adjusted to the proper tightness. The bars are adjustably held in the sockets preferably by nails c'' engaging notches d'' which prevent the frames from bending apart sufficiently to drop the bars. One end of each bar is screwthreaded and has a nut e'' which can be screwed outwardly to spread the bars and stretch the cloth. The nut can then be held against unscrewing in any manner.

As thus far described the apparatus is adapted for any of the ordinary uses of such devices, but when it is desired to collect the product at either side or the middle of the screen instead of discharging it throughout the width thereof, I provide a supplemental base V having a conveyer W beneath the fine outlet and a conveyer X beneath the coarse outlet, which conveyers have bearings in castings Y and are driven from the shaft D by a sprocket chain Z . These conveyers have troughs consisting of two pieces f'' and g'' , the latter having a notch in one end for an outlet. These two pieces are arranged end to end with the notch in the center or at either end of the conveyer, according to where discharge of the product is desired. The conveyers are identical with the feed conveyer B , except that one is a right hand conveyer and the other a left hand conveyer, and each is made in two equal pieces with the shafts extending entirely through them to support the adjacent ends, so that if central discharge is desired for each lower conveyer, this can be accomplished by putting a piece of right hand and a piece of left hand conveyer on each shaft, whereas if end discharge is desired, like pieces of conveyer will be put together. Should it be necessary to put the feed hopper at the center, two reverse pieces of conveyer will be used in the feed trough, and the feed conveyer will be used below. In such case it will be necessary for one of the lower conveyers to have an end discharge and the other a central discharge.

In operation the apparatus may be adjusted to suit any requirements as to feed, discharge angularity or extent of vibration.

- It is accessible from front, rear, top or bottom. It can be ventilated by opening the back door R and the front door Q, or either of them. The greater steepness of the bottom will insure downflow of the fine material, even when the screen proper is adjusted below the usual steepness. The screen frames can be removed individually through the front or rear, or through the bottom or top.
- For packing the feet and legs can be folded against the body, and great compactness obtained. Assembly and disconnection can be quickly effected, and adjustment of either spring pressure or extent of vibration is easily obtained. The drive pulley and vibrating arms can be placed on either side, and the oscillating bearings will rock in their brackets to compensate for any skewing of the frame due to uneven setting.
- The various details of construction, arrangement and combination shown each constitute a feature of improvement and a part of my invention, and it will be understood that I do not limit myself to the particular adaptation herein set forth as constituting the preferred form of my invention, since the same may be availed of in whole or in part, according to such modifications as the judgment of those skilled in the art may dictate, without departing from the spirit of my invention.
- I prefer to also use an adjustable knocking stop rod *i* over the middle of the screen, to limit vibration there due to the resiliency of the longitudinal and transverse bars or supports *i*, *o* and *p*. This has the same effect as the flanges *s*.
- While I have herein shown and described the feeder set forth the same is not claimed in this application, being the subject matter of claims in my application Serial No. 454, 604, filed September 24, 1908, of which this application is a division.
- I claim as my invention:—
1. In combination, a frame or casing, a removable inclined screen therein comprising a rectangular frame, a wire mesh screen clothing mounted thereon, resilient means under the downwardly inclined side edges of said frame affording supports on which said screen is separably mounted, means for depressing said screen, and means above and sustained by said supports for jarring said screen.
  2. In combination, a frame or casing, a removable inclined screen thereon comprising a resiliently mounted rectangular frame and wire mesh clothing stretched thereon, resilient means under and affording supports for the edges of said frame, means above the edges of said frame for resisting upward movement thereof, and impact members for jarring said screen sustained thereon.

3. In combination, a frame or casing, removable inclined screens therein comprising a rectangular frame and wire mesh clothing mounted thereon, flexibly mounted longitudinal supports on which said screens are separably fastened, impact members above said supports for jarring said screens, and swinging strikers within said casing, above and acting downwardly on said members for percussively jarring said screens.

4. In combination, a frame or casing, a removable inclined screen therein comprising an oblong rectangular screen frame and a wire mesh clothing mounted thereon, resilient supports under the longitudinal edges of said frame on which said screen is mounted, means above the edges of said screen for limiting upward movement thereof, and jarring means for said screen supported thereby.

5. In combination, a frame or casing, a removable inclined screen therein comprising a rectangular screen frame and a wire mesh clothing, flexible supports on which said screen is removably mounted, adjustable impact members above said screen for jarring it, and means for percussively acting on said members.

6. In combination, a frame or casing, a removable inclined screen thereon comprising a rectangular frame and wire mesh clothing mounted thereon, a flexible support on which said screen is removably mounted, an upwardly extending impact member mounted on said support for jarring said screen, and a swinging striker acting percussively on said member, one of said latter parts being adjustable.

7. In combination, a frame or casing, a removable inclined screen therein comprising a rectangular screen frame and screen clothing mounted thereon, and a support for the downwardly inclined edge of said screen frame comprising a downwardly extending inclined member sustaining said screen and having a downwardly extending groove or recess on its upper side beneath the edge of said screen, and an impact member mounted on said screen.

8. In combination, a frame or casing, a removable inclined screen therein, and a support for the downwardly inclined edges of said screen comprising downwardly extending inclined members beneath and sustaining said edges respectively, and each having a downwardly extending groove or recess on its upper side beneath the adjacent edge of said screen for receiving leakage from such edge, and impact members mounted on said screen.

9. In combination, a frame or casing, a removable inclined screen therein comprising a rectangular screen frame and a foraminous cover mounted thereon, and a support for said screen frame comprising a bar or mem-

ber under and extending longitudinally of its edge, and having an upwardly extending flange or portion engaging the under side of said screen frame and sustaining it, and impact members sustained by said screen.

10. In combination, a frame or casing, a removable inclined screen therein comprising a screen frame and screen clothing mounted thereon, and a support for the edge 10 of said screen frame comprising a member extending longitudinally of and sustaining said edge and having an upwardly extending flange or part projecting within said frame, and impact members sustained by 15 said screen.

11. In combination, a frame or casing, a removable inclined screen therein comprising a screen frame and screen clothing mounted thereon, and a support for the opposite edges of said screen frame comprising members extending longitudinally of said edges respectively and each having a projecting flange or part extending within said screen frame and sustaining the latter, and 25 impact members carried on said screen.

12. In combination, a frame or casing, a plurality of removable screens therein, each comprising a foraminous screen member and a projecting edge or frame carried thereby, 30 and a support for the adjacent edges of two of said screens, comprising a member extending longitudinally thereof and having projecting parts or flanges spaced apart to afford a groove or recess for receiving the 35 projecting edges or frames of two adjacent screens, said flanges or parts projecting within the inner sides of said edges or frames and sustaining said screens, and impact members mounted on said screens.

13. In combination, a frame or casing, a plurality of removable inclined screens therein, supports near the sides of said casing for the inclined edges of said screens respectively, and a support intermediate of the 40 sides of said casing for the adjacent inclined edges of two of said screens, comprising a downwardly inclined member beneath the edges of two of said screens and having upwardly extending flanges sustaining the adjacent edges of two of said screens respectively, and impact members mounted on said screens.

14. In combination, a frame or casing, removable inclined screens therein comprising screen frames and screen clothing mounted thereon, means supporting said screens near the sides of said casing, a flexible support for said screens intermediate of said sides, and a stop or abutment above the intermediate part of said screens for limiting upward movement thereof.

15. In combination, a frame or casing, a removable resilient inclined screen therein comprising a rectangular screen frame and screen clothing mounted thereon, a support

under the edge of said screen, and jarring means above the edge of said screen mounted on said support.

16. In combination, a frame or casing, a removable oblong inclined screen therein, 70 supports under the edge of said screen, and jarring means above the longitudinal edge of said screen sustained by said edge.

17. In combination, a frame or casing, a removable oblong rectangular inclined screen 75 therein, resilient supports under the longitudinal edge of said screen, and jarring means for said screen mounted on said edge.

18. In combination, a frame or casing, a removable inclined screen therein, resilient 80 supports under said screen, and jarring means above the edges of said screen comprising impact members resting thereon.

19. In combination, a frame or casing, an inclined screen therein, means resiliently 85 supporting said screen, and jarring means on the edge of said screen sustained by said supports and means.

20. In combination, a frame or casing, a removable inclined resilient screen therein, 90 and a plurality of jarring means spaced apart from one another along the edge of said screen and sustained thereon.

21. In combination, a frame or casing, a plurality of removable inclined screens resiliently mounted thereon, and each comprising a rectangular frame or casing and a screen clothing stretched thereon, said screens disposed in parallelism, resilient means beneath and supporting adjacent 100 edges of two of said screens, and means for jarring said screens and sustained thereon.

22. In combination, a frame or casing, a plurality of removable inclined screens mounted thereon, bars or members extending transversely of said casing beneath and supporting said screens and spaced apart from the bottom of said casing, and means above for jarring said screens supported thereby.

23. In combination, a frame or casing, a plurality of removable inclined screens mounted thereon, a bar or member extending transversely of said casing beneath and resiliently supporting the edge of two of 115 said screens, and means for jarring said screens supported on their edges.

24. In combination, a frame or casing, a removable inclined screen therein, and impactive jarring means above, opposite, acting downwardly toward, and sustained by, the edge of said screen.

25. In combination, a frame or casing, a removable inclined screen therein, and jarring means therefor comprising removable 125 impact members above the edge of said screen and sustained thereby.

26. In combination, a frame or casing, a removable inclined screen exerting an upward stress therein, and comprising a frame 130

and a screen clothing mounted on top of said frame, means resisting such stress above and opposite and engaging the edge of said screen for limiting its upward movement, and downwardly acting percussive means for jarring said screen acting impactively on the edge of the latter.

27. In combination, a frame or casing, a screen or member therein, and means for moving the latter comprising impact faces mounted on said screen or member and spaced apart to afford a recess or space between them, and a swinging striker pivotally mounted opposite said recess or space and acting impactively on said faces alternately.

28. In combination, a frame or casing, a screen or member therein, and means for moving the latter comprising a part mounted thereon and having projecting impact faces affording a recess between them, and a swinging striker pivotally mounted in said recess and acting on said faces.

29. In combination, a frame or casing, a screen mounted thereon, and means for jarring said screen comprising a swinging member for depressing said screen, a stop for arresting upward movement of said screen, and means pressing said screen toward said swinging member.

30. In combination, a frame or casing, an inclined screen mounted thereon, springs at the edge of said screen for pressing it upwardly, means sustained on the edge of said screen for depressing it, and stops or abutments at the edge of said screen for arresting its upward movement.

31. In combination, a frame or casing, a screen or member mounted thereon, and means for moving the latter comprising an axial shaft or stud, an oscillating striker carried thereby, and an impact member mounted on said screen or member and having impact faces disposed at opposite sides of and in approximately the same plane as the axis of said striker and acted on by the latter.

32. In combination, a frame or casing, a screen or member mounted thereon, an oscillating part pivotally mounted opposite said screen and having striking faces at each side of its pivotal axis, means causing said screen or member to exert a stress toward said part, and projecting means connected to said screen or member and engaging the striking faces of said part at opposite sides of its pivotal axis.

33. In combination, a frame or casing, a movable screen or member mounted thereon, an oscillating part and projecting means connected to said screen or member straddling the axis of said part and engaged by the latter thereby to move said screen.

34. In combination, a screen comprising a woven mesh screen clothing and a frame

on which said clothing is mounted, and means for stretching said clothing comprising an expansible transverse member mounted on said frame between the upper and lower faces thereof, and comprising a compression member extending from one to the other side of said frame and spaced apart from said screen clothing to afford a clearance between it and the latter throughout the width of said frame.

35. In combination, a screen comprising a woven mesh screen clothing and a frame on which said clothing is mounted, and means for stretching said clothing comprising an expansion member crossing said frame mounted thereon above the lower face thereof, and spaced above the plane of the lower face of said frame for affording a clearance within the lower side of said frame.

36. In combination, a screen comprising a woven mesh screen clothing and a frame on which said clothing is stretched, and means for stretching said clothing comprising an expansion member mounted on the inner side of said frame between the upper and lower faces thereof and extending between the sides of said frame beneath and spaced apart from said clothing to afford a clearance between it and the latter.

37. In combination, a screen comprising a woven mesh screen clothing and a frame on which said clothing is mounted, and means for stretching said clothing comprising a single compression member mounted on said frame and extending across the latter beneath and spaced apart from said clothing to afford a clearance beneath the latter, and having ends abutting against said frame above and spaced apart from the lower face of said frame to afford a clearance within the latter.

38. In combination, a screen comprising a woven mesh screen clothing and a frame on which said clothing is stretched, and means for stretching said clothing comprising a compression member crossing said frame beneath and spaced apart from said clothing, and affording a clearance above the lower face of said frame, and means for adjusting said member.

39. In combination, a screen comprising a woven mesh screen clothing and a frame on which said clothing is mounted, and means for stretching said clothing comprising an unyielding compression member crossing said frame beneath and spaced apart from said clothing, and a screw for adjusting said member positively.

40. In combination a frame or casing affording a screening chamber, removable inclined screening means therein, a casing or housing above said screening means providing a feeding chamber, an inclined member providing a partition between said screen.

ing and feeding chambers and affording an outlet from said feeding chamber above said screening means, and a door or cover for said casing below said inclined member affording a ventilating outlet for said screening chamber below said partition, and above said outlet.

In witness whereof, I have hereunto signed my name in the presence of two subscribing witnesses.

GEORGE HOLT FRASER.
